UNITED STATES PATENT OFFICE.

DANIEL McRAE, OF CENTRAL ISLIP, NEW YORK.

ROWING-GEAR.

1,346,040.

Specification of Letters Patent.

Patented July 6, 1920.

Application filed February 17, 1920. Serial No. 359,424.

To all whom it may concern:

Be it known that I, DANIEL McRAE, a citizen of the United States, and resident of Central Islip, in the county of Suffolk and 5 State of New York, have invented a new and Improved Rowing-Gear, of which the following is a full, clear, and exact description.

This invention relates to a rowing gear 10 and more particularly to an improvement in an oar lock.

In the general construction of oar locks now in use, considerable friction is incurred by the oar when making the stroke or 15 feathering, said friction resulting in wear on the oar and the inner face of the stirrup of the oar lock.

It is therefore one of the principal objects of this invention to overcome the above 20 recited objections by providing an oar lock with means which will greatly reduce the friction between the parts and minimize wear on the same.

Another object of the invention is to provide 25 an oar lock provided with simple and effective anti-friction means constituting a part thereof.

With these and other objects in view which will be more readily apparent here- 30 after, reference is made to the following description, claims and accompanying drawings forming a part of this application, and in which—

Figure 1 illustrates a perspective view of 35 the improved oar lock.

Fig. 2 is a fragmentary vertical sectional view therethrough taken approximately on the line 2—2 of Fig. 3.

Fig. 3 is a transverse sectional view taken 40 approximately on the line 3—3 of Fig. 2.

Fig. 4 is a detailed sectional view taken on the line 4—4 of Fig. 2.

Referring to the drawings by characters of reference which denote like parts 45 throughout the several views thereof, 10 designates the stirrup of an oar lock, the free extremities of which constitute the horns 11. A bearing pin 12 is secured to the medial portion of the outer surface of the 50 stirrup 10 for mounting the oar lock in the socket of the gunwale of a boat. The stirrup is preferably of hollow construction and the major portion of the inner face thereof is provided with a slot 13 which is 55 rabbeted as at 14 to receive the positioning flanges 15 formed on the inner face of a

cover member 16. The cover member is provided with a slot 17 having beveled faces 18, the restricted portion thereof being disposed outwardly as clearly illustrated in 60 Fig. 4 of the drawings. Attaching screws 19 are passed through the extremities of the cover member and threadedly engaged with the stirrup adjacent the horns 11. The anti-friction members 20 are adapted 65 to be arranged in the slotted portion 13 of the stirrup and the same are retained therein by the cover member which permits a portion of the anti-friction devices 20 to protrude from the slot 17. By this arrangement it will be understood that when an oar 70 is arranged within the stirrup of the oar lock, the same will bear upon the anti-friction devices 20 whereby to minimize friction on the oar when making the stroke or 75 feathering.

While there has been illustrated and described a single and preferred embodiment of the invention, it is to be understood that no limitation is made to the manner of associating the anti-friction devices with the stirrup of the oar lock nor any of the other details of construction, as alterations and modifications falling within the scope of the appended claims may be resorted to 80 when found expedient.

Having thus described my invention, what I claim as new and desire to secure by Letters Patent is,

1. In an oar lock, the combination with 90 the stirrup thereof, of anti-friction devices carried thereby and protruding from the inner face thereof, said anti-friction members constituting a bearing surface for directly receiving an oar.

2. In an oar lock a stirrup therefor having a groove formed in the inner face thereof, anti-friction members arranged therein and means for retaining said anti-friction members in said groove, said anti-friction 100 members constituting a bearing surface for directly receiving an oar.

3. An oar lock comprising a bearing pin, a stirrup therefor having a groove formed in the inner face thereof constituting a 105 race-way, anti-friction members arranged in said race-way and a slotted cover section secured to the inner face of said stirrup for retaining anti-friction members in the race-way.

DANIEL McRAE.
